CLAIM

I claim an ornamental design for a shopping kiosk, as shown and described.

DESCRIPTION

FIG. 1 is a front perspective view of a shopping kiosk in accordance with the design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, shown in use wherein two pieces of environmental clothing are hung on bars of the shopping kiosk.

The broken lines in the drawings depict unclaimed environment only and form no part of the claim.
